UNITED STATES PATENT OFFICE.

GEORGE H. BODINE, OF ZANESVILLE, OHIO.

DESIGN FOR A BUILDING-BLOCK.

SPECIFICATION forming part of Design No. 25,044, dated January 7, 1896.

Application filed December 4, 1895. Serial No. 571,058. Term of patent 7 years.

To all whom it may concern:

Be it known that I, GEORGE H. BODINE, a citizen of the United States, residing at Zanesville, in the county of Muskingum and State of Ohio, have invented and produced a new and original Design for Building-Blocks, of which the following is a specification, reference being had to the accompanying drawings, showing a part thereof.

Figure 1 is a side elevation. Fig. 2 is a plan view. Fig. 3 is a section on about line 3'3 of Fig. 2, and Fig. 4 is a section on about line 4'4 of Fig. 3.

The leading feature of my design consists in the external and internal configuration of the block, the exterior of which is in the form

of a cubical rectangular block with plane uniform surfaces on five sides, its sixth side A presenting centrally a circle B, marking the mouth of the interior of the block.

Interiorly the block presents a cylindrical form ranging from the circle B nearly to the inner end of the cavity C, the inner end of which is concaved, as shown most clearly in Fig. 4.

What I claim is—

The design for a building block herein shown and described.

GEORGE H. BODINE.
